UNITED STATES PATENT OFFICE.

WILLIAM T. HOOFNAGLE, OF GLEN RIDGE, NEW JERSEY, ASSIGNOR TO COMFO ELECTRIC IRON COMPANY, OF GLEN RIDGE, NEW JERSEY, A CORPORATION OF NEW JERSEY.

ELECTRIC FLATIRON.

Application filed June 1, 1921. Serial No. 474,105.

To all whom it may concern:

Be it known that I, WILLIAM T. HOOFNAGLE, a citizen of the United States, residing at Glen Ridge, in the county of Essex 5 and State of New Jersey, have invented certain new and useful Improvements in Electric Flatirons, of which the following is a specification.

This invention relates to improvements in 10 electrically heated flat irons, and more particularly to protective means for preventing the iron from being over-heated and causing damage by scorching or fire, or injury to its own heating element, in case the operator 15 fails to cut off the electric current when the iron is not being used.

In carrying out the invention, I provide a recess in the metal body of the iron and within this recess is arranged an ordinary 20 fuse plug, the base terminal of the fuse being in contact with the body of the iron. I also provide in the casing or cover of the iron a sight opening, and beneath this sight opening is arranged a platinum or other non- 25 oxidizable wire, this wire and the fuse being in series with the heating coil in the iron. With this arrangement, while the current is on, the platinum wire becomes heated by the current and more or less luminous so that 30 the operator may, by looking at the wire through the sight opening, determine whether or not the current is on, and if the operator fails to heed this visual signal and cut off the current, when the iron is not in 35 use, then the iron will be automatically cut off by the melting of the fuse which will result from its direct contact with the over-heated iron body.

In the accompanying drawing,

40 Fig. 1 is a side elevation of a flat iron embodying my invention, the enclosing casting of the iron being shown in central section;

Fig. 2 is a top plan view of the same with 45 the cover and handle removed, the heating coils being shown in dotted lines and the body of the iron being partly broken way; and,

Fig. 3 is a section on the line 3—3 of Fig. 50 2, on a smaller scale.

Referring to the drawing, 1 and 2 indicate the metal parts of the body which are to be heated and between which is clamped the heating coil 3, by bolts 4, passing through 55 the part 2 into the part 1, this arrangement

of parts being well known. The arms 5 to which the handle 6 is secured are connected to the bolts 4, and a top or cover 7 encloses the various parts except the base. The bolts 4 are electrically insulated from the body 2 by 60 washers 4^a and bushings 4^b and by the covering of the heating coil which is usually of mica. In the metal body 2, I provide a recess 8, and mounted upon said body is a socket *a*, adapted to receive a fuse plug *b*, 65 such as is ordinarily used on electric lighting circuits. The socket *a* comprises the insulating ring 9, having a threaded metal shell 9^a, which extends into the recess 8, this shell being screw-threaded and adapted to 70 be engaged by the outer threaded band 10 on the plug. The base terminal 11 of the plug rests upon the metal body 2, at the bottom of the recess so as to make electrical contact with said body and also in order that the 75 fuse may be heated by the body. A metal rod 12, electrically connected to the shell of the socket by a screw 13, extends transversely of the iron above the body 2, and a platinum or other non-oxidizable wire 14 connects the 80 end of this rod with another metal rod 15, which is secured to one of the terminals, 16, through which current is supplied to the iron. The other terminal 17 is connected directly to one end of the heating coil 18, 85 and the other end of said coil terminates in a flat metal part 19, which contacts with the bottom of the body 2. The electrical circuit proceeds from the terminal 17, through the heating coil to the contact 19, thence through 90 the metal body 2 to the base terminal of the fuse plug, thence through the fuse 20 to the threaded band 10, thence through the shell of the socket to the screw 13, and from the screw 13, through rod 12, 95 platinum wire 14 and rod 15 to the terminal 16. When current is flowing through this circuit, the platinum wire becomes luminous and is visible through a sight opening 21 in the casing 7.

The current is carried to the iron through the usual flexible cord 22 and socket 23, which fits on to the terminals 16 and 17.

In operation, while the current is on, the wire 14 is luminous, and if the operator stops 105 using the iron without cutting off the current, this luminous wire will indicate to the operator that the current has not been cut off, and in most cases the operator will then cut off the current; but should the operator 110

fail to heed this visual signal, the fuse will become so hot by reason of its contact with the metal body that it will melt and interrupt the circuit.

5. What I claim is:

1. In an electrically heated flat iron, a metal body to be heated, a socket, adapted to receive a fuse plug, mounted on said body, a fuse plug fitting said socket and having a 10 base terminal engaging said body, a heating resistance in the iron, and a circuit including

said resistance, body, and fuse plug.

2. In an electrically heated flat iron, a metal body to be heated, a fuse plug having a terminal engaging said body, a cover for 15 said body having a sight opening, a filament below said opening, a heating resistance in the iron, and a circuit including said resistance, body, fuse plug and filament.

In testimony whereof I affix my signature. 20

WILLIAM T. HOOFNAGLE.
